UNITED STATES PATENT OFFICE.

WILLIAM M. SCHLESINGER, OF PHILADELPHIA, PENNSYLVANIA.

REGULATOR FOR DYNAMO-ELECTRIC MACHINES.

SPECIFICATION forming part of Letters Patent No. 331,552, dated December 1, 1885.

Application filed September 19, 1885. Serial No. 177,539. (No model.)

To all whom it may concern:

Be it known that I, WILLIAM M. SCHLESINGER, a subject of the Queen of Great Britain, residing at Philadelphia, in the county of 5 Philadelphia and State of Pennsylvania, have invented certain new and useful Improvements in Regulators for Dynamo-Electric Machines, of which the following is a specification, reference being had therein to the accompanying 10 drawing, which is a diagrammatic view showing devices embodying my improvements.

My invention has relation to dynamo-electric machines in general, but particularly to those for feeding the line-conductors for an 15 electric railway or other translating devices; and it has for its object to regulate the dynamo to give a certain difference in potential on the brushes of the generator or between two points on its outside circuit, and to prevent the dynamo overheating by reason of it generating 20 too great a current.

My invention accordingly consists in taking a loop or branch from the main conductors, placing a solenoid or magnet therein the core 25 or armature of which acts upon switching devices, one part of which is also controlled or operated by a solenoid or magnet in circuit with one of the line-conductors, either or both of which act to change the direction of the 30 current to and from a current-regulating device in circuit with the field-magnet coils of the dynamo, whereby the current generated by the dynamo is never permitted to rise above a desired point or limit, all of said parts being 35 constructed, combined, and arranged for operation as hereinafter described and claimed.

In the drawing, A A' represent the line-conductors; A², the generator or dynamo-electric machine therefor. a a' is a loop from 40 conductors A A', including a solenoid, B, which is of a high resistance, and the core b of which has a retracting-spring, b', provided with an adjusting-screw, b². To the lower end of core b² is attached a non-conducting strip, b³, which 45 engages with levers c c', pivoted, respectively, at c² c³ to a standard, c⁴. These levers are electric conductors insulated from each other by standard c⁴, and from their pivot-points proceed wires or connections d d', preferably forming a second loop from conductors A A'. The 50 free ends of levers c c' are adapted to metal strips e e' e² on an insulating-strip, f', secured

to a core, f, of a solenoid, F, which is of a low resistance. The core f is provided with a retractile spring, f², having an adjusting-screw, 55 f³. From strips e e' e² lead connections 1 2 3 to a regulating device, G, of any of the well-known automatically-acting forms, in circuit by way of wires x x with the field-coils of dynamo A². The solenoid F is included in the line of one 60 of the conductors, and its core f, as well as that of solenoid B, are provided with stops h, for limiting their upward movement; and h' are additional stops suitably located for limiting the reverse movement of said cores. 65

The tension of the spring f² is adjusted to maintain the core f in position within solenoid F, according to the limit of current desired for the dynamo, and the tension of spring b' is adjusted to maintain core b in solenoid B according to the difference of potential desired 70 on the brushes of the generator or between any two points on its outside circuit or line-conductors. If the said difference of potential on the brushes or on the outside circuit of the 75 generator is the desired one, the core b of the solenoid B holds the levers c c' out of contact with the metal strips e e' e², as shown; but should said difference of potential sink or rise said levers will in the first case be moved by 80 the elevation of core b in solenoid B to contact, respectively, with strips e' e², and in the second case with strips e and e', due to the downward movement of said core, allowing a current in the one case to flow from d e 85 e' through regulating device G, entering by way of wire 2 at g', and leaving at g, and thence passing by way of wire 3 to e², c', and d' to conductor A', and in the other case from d c e and wire 1 to regulator G, entering at g 90 and leaving at g', and thence by wire 2 to e', c', and d' to conductor A', thereby causing the regulator to act upon the field of the dynamo to maintain a fixed difference of potential on the brushes or between the points on the outside circuit of the generator by raising its 95 electro-motive force in the first case and reducing it in the second case until such limit is reached.

As the quantity of current generated by the 100 dynamo rises above a certain fixed point or limit, above which it tends to injure the dynamo, the core f in solenoid F is pulled down by the current passing through it by reason of

such current, making the solenoid strong enough to overcome the tension of spring f^2 , so that strip e touches lever c , and strip e' touches lever c' , thereby establishing the circuit through d c e wire 1 g G g' e' c' d' , and, thus reducing the electro-motive force of the generator, spring b' will then raise core b of solenoid B until stop h thereof prevents further rising, while at the same time core f of solenoid F sinks, keeping ee' in contact with c and c' , respectively, until the current reaches the limit.

If the current remains at or sinks below the limit, core f will be pulled up by spring f^2 until stop h thereof stops such upward movement, allowing the solenoid B to act to again regulate the electro-motive force, as above described. The dynamo will therefore never give a current which is too large for it or one which might heat it too much.

Instead of using the solenoids B F, magnets with armatures may be substituted therefor.

When both solenoids are used, as above described, they successively or coincidently act, as above described, to fix the limit both of the electro-motive force of the dynamo and the amount of current generated.

Instead of making the wires d d' lead or loop from both conductors, A A', they may loop from only one, or the conductor A, by placing a suitable resistance, l , therein in advance of wire d , connecting or looping wire d' , as shown by dotted line l' , to the opposite end of the resistance, which is also connected to or forms part of the conductor A, as represented by dotted line l'' .

What I claim is—

1. The combination, with a dynamo-electric generator and its line-circuit, of a loop from the

line-circuit having an electro-magnet with 40 armature, a circuit-changing switch in engagement with said armature, a second loop from the line-circuit leading to said switch, an electro-magnet included in one of the conductors of the line-circuit, and provided with an armature 45 having insulated blocks forming part of said reversing-switch, and a regulator in circuit with the field-magnets of the generator and with said insulated blocks, substantially as and for the purpose set forth.

2. The combination, with a dynamo-electric machine or generator and its line-circuit, of a loop from the line-circuit having an electro-magnet with armature, a circuit-changing switch in engagement with said armature, a 55 second loop from the line-circuit leading to said switch, and a regulator in circuit with the field-magnets of the dynamo, and with said switch, substantially as and for the purpose set forth.

3. The combination, with a dynamo-electric machine and its outside circuit, of a loop from said circuit having a high-resistance magnet with armature, a circuit-changing switch in engagement with said armature, a low-resistance magnet having an armature and located in the circuit of one of the conductors of said outside circuit, insulated blocks on said armature forming part of said switch, and a regulator in circuit with the field-magnets of the 70 dynamo and with said insulated blocks, substantially as and for the purpose set forth.

In testimony whereof I affix my signature in presence of two witnesses.

WILLIAM M. SCHLESINGER.
